UNITED STATES PATENT OFFICE

DAVID MCCHESENEY, OF KIRKLAND LAKE, TIMISKAMING, ONTARIO, CANADA

WALL-BOARD JOINT

Application filed March 14, 1930. Serial No. 435,901.

My invention relates to improvements in wall board joints, and the object of the invention is to devise a strong joint between the meeting edges of the boards which will provide a surface over the joints perfectly flush with the outer face of the board, and which will therefore, not be visible through any surface finish such as paint or paper applied to the face of the boards, and it consists essentially of the arrangement and construction of parts hereinafter more particularly explained.

Fig. 1 is a perspective view of a fragmentary portion of a wall board construction showing my joint applied thereto.

Fig. 2 is a sectional view taken transversely of the joint.

In the drawing like letters of reference indicate corresponding parts in each figure.

1 indicates a portion of the frame of a building to which the wall boards are applied. 2, 3, 4 and 5 are the corner portions of a plurality of wall boards applied to the frame with their meeting edges abutting. 25 Each of the wall boards is provided with an edge depression or recess 6 forming vertical or horizontal channels when the boards are assembled.

7 are metallic strips preferably formed of sheet metal which fit the channels formed by the recesses 6 being secured in place by nails 8 and 9 extending through perforations formed therein in proximity to their edges and through those portions of the wall boards forming the base of the recesses 6 into the frame 1.

The strips 7 are counter sunk beneath the surface of the wall board as clearly indicated in Fig. 2, and the channel formed by the recesses 6 is then filled with a suitable plastic filling such as gyproc filling so as to produce a surface over the joint which is flush with the face of the wall board.

When the joint is finished as above described it will be readily seen that a continuous smooth surface is provided through which the joint will not be visible and will thereby permit of the face of the wall board being painted or papered without the surface being in any way marred by any slight

indication of the joint appearing therethrough.

From this description it will be seen that I have devised a very simple and yet strong and durable joint for connecting the meeting edges of wall boards together, which will be invisible when completed permitting the decorating of the wall board surface without being marred by any visible appearance of the joint through such decoration.

What I claim as my invention is:

In a wall board joint construction, the combination with two adjacent wall board portions made from a plastic material and having edge recesses forming a groove, a metallic plate countersunk in the groove, securing nails extending through the plate adjacent each edge thereof and through the adjacent edges of the wall boards, and a filling for the groove flush with the outer face of the wall board.

DAVID MCCHESENEY.
